UNITED STATES PATENT OFFICE

EDWARD L. ROSENFIELD, OF CLEVELAND HEIGHTS, OHIO, ASSIGNOR TO THE GRABLEER MANUFACTURING COMPANY, OF CLEVELAND, OHIO, A CORPORATION OF OHIO

BAG HOLDING AND FILLING DEVICE

Application filed July 16, 1928. Serial No. 292,926.

This invention relates to means for holding bags while they are being filled, and for facilitating the filling of the bags; and its general objects are to provide a relatively simple and inexpensive means of the aforesaid nature that is especially convenient of use, that is rugged, substantial and durable, that greatly expedites the bag filling operation, and that is non-adjustable yet is equally suitable for use with bags of various sizes throughout a considerable range.

According to the present disclosure, the invention is incorporated in a hand truck, although it is to be understood as not limited to such an association. Essentially, the invention consists of a supporting structure, a funnel or hopper carried thereby, and a device for sustaining the bag, preferably at two points located on opposite sides of the discharge spout of the funnel or hopper, with the mouth of the bag drawn about the spout, said spout serving to maintain the mouth of the bag open during the filling operation.

A further object of the invention is to provide supporting means to which the bag may be very quickly and easily applied by simply engaging the material of the bag over hooks or the like, and from which the bag may be disengaged with even greater ease by simply releasing the supporting means, allowing it to collapse or drop and thereby disengage itself from the bag, or assume such a position that the bag may be lifted away from the device without interference.

The foregoing objects, with other and more limited ones hereinafter appearing, are obtained in the embodiment of the invention illustrated in the accompanying drawings wherein Fig. 1 is a side elevation, and Fig. 2 a front elevation, of my improved bag holding and filling means; Fig. 3 is a section on the line 3—3 of Fig. 1; Fig. 4 is an enlarged sectional detail of the bag sustaining device, and Fig. 5 is a perspective view thereof.

As previously stated, the invention is shown as incorporated in a hand truck and from the standpoint of utility this makes a very practical and convenient combination. For the present purpose, however, the hand truck may be regarded broadly as a sup-

porting frame or structure, and obviously such frame or structure could be applied to, or mounted upon, a platform or other type of scale so that a given quantity of the commodity that is to be placed within the bag could be deposited therein, as would be indicated by the scale, in the initial filling of the bag. Such an application of the invention is so apparent that specific illustration thereof is deemed unnecessary.

The supporting frame or structure is designated, generally, by the reference numeral 1, and supported by, and forwardly of, its upper portion, as by means of brackets 2 and 3, is a hopper 4 having a discharge spout 5 about which the mouth of a bag 6 is adapted to be drawn. In applying the bag to the hopper, the material of the bag is gathered together on opposite sides of the spout 5 and engaged over relatively sharp and thin hooks 7 that are suitably connected, as by rivets 7a, to the forward ends of arms 8, the rear ends of said arms being shown as turned inwardly and riveted or otherwise secured to a cross bar 9 whose ends are formed with trunnions 9a journaled in brackets 10 that are suitably connected to and project slightly forwardly of the side members of the supporting frame or structure 1. The cross bar 9 and arms 8, with their hooks 7, make up a yoke that constitutes the bag holding means.

Applied to the rear side of the cross bar 9 at about its longitudinal center is a handle 11, and extending from one side of this handle is a headed stud 11a that is engaged through an L-slot 12a in a latch plate 12, said plate being pivoted at 13 to a bracket 14 that is fastened to a transverse member 15 of the supporting frame or structure 1. The yoke, comprising the parts 8 and 9, is held in bag sustaining position by means of the latch plate 12, this end being effected by the engagement of the stud 11a within the offset lower end of the slot 12a. After the desired amount of material has been placed within the bag, the latch plate 12 is swung forwardly at its upper end to remove the stud 11a from the offset lower end of the slot, whereupon the stud is free to rise within the slot, permitting the handle 11 to be elevated so

that the arms 8 may drop and allow the bag to fall away from the spout 5 of the funnel or hopper 4. When the bag holding or sustaining means thus collapses, the hooks 7 either 5 withdraw from the material of the bag, or assume such a position that the bag may be lifted therefrom without interference. Preparatory to applying another bag to the holding means, the handle 11 is swung downwardly and is automatically locked in its depressed position by the latch plate 12 gravitating to effective position wherein the stud 11^a occupies the offset lower end of said slot. With the handle held depressed, the arms 8 10 are, of course, retained in bag holding position.

Having thus described my invention, what I claim is:

1. In a device of the character described, the combination of a supporting structure, a hopper sustained thereby, said hopper having a discharge spout, a yoke pivoted to the supporting structure and incorporating arms that are disposed on opposite sides of the spout when the yoke is in bag sustaining position, a handle on the yoke for swinging it to said position, a latch carried by the supporting structure for cooperation with said handle to maintain the yoke in bag sustaining position, and means on said arms wherein with a bag is adapted to be engaged at restricted points on opposite sides of the spout of the hopper for holding the bag with its mouth spread open by the spout.
2. In a bag holding device of the character described, the combination of a supporting frame, a cross bar pivotally connected at its ends to said frame, arms extending from one side of said cross bar and spaced apart longitudinally of the bar, a handle extending from the opposite side of said cross bar, means releasably holding the parts in a position with said arms substantially horizontal, and bag attaching means carried by the free 45 ends of said arms.
3. In a bag holding device of the character described, the combination of a supporting frame, a cross bar pivotally connected at its ends to said frame, arms extending from one side of said cross bar and spaced apart longitudinally of the bar, a handle extending from the opposite side of said cross bar, a latch movably connected to the supporting structure for cooperation with a part 50 on said handle for holding the parts in a position with the aforesaid arms substantially horizontal, and bag attaching means carried by the free ends of said arms.
4. In a bag holding device of the character 55 described, the combination of a supporting frame, a cross bar pivotally connected at its ends to said frame, arms extending from one side of said cross bar and spaced apart longitudinally of the bar, a handle extending from the opposite side of said cross bar, a latch

comprising two cooperating elements that are carried, respectively, by the handle and the supporting structure for holding the parts in a position with the aforesaid arms substantially horizontal, and bag attaching means carried by the free ends of said arms. 70

5. In a bag holding device of the character described, the combination of a supporting frame, laterally spaced brackets carried by said frame, a cross bar trunnioned at its ends in said brackets, arms extending forwardly from the cross bar and spaced apart longitudinally thereof, bag attaching means carried by the free ends of said arms, a handle extending from the side of the cross bar 75 opposite that from which said arms project, a latch plate pivotally connected to the supporting frame and disposed adjacent said handle, said latch plate having a slot provided with an offset portion, and a stud extending from said handle through said slot and arranged to be engaged within the offset portion of the slot when the aforesaid arms are in bag sustaining position.

6. In a bag holding device of the character described, the combination of a supporting frame, laterally spaced brackets carried by said frame, a cross bar trunnioned at its ends in said brackets, arms extending forwardly from the cross bar and spaced apart longitudinally thereof, relatively thin and sharp bag attaching hooks carried by the free ends of said arms, a handle extending from the side of the cross bar opposite that from which said arms project, a latch plate having a keeper, and a member for engagement with said keeper, the latch plate and member being carried, respectively, by the handle and the supporting frame, and cooperating to hold the parts against movement when the aforesaid arms are in bag sustaining position. 90

In testimony whereof, I hereunto affix my signature.
